(57) **CLAIM**

The ornamental design for a key with bottle opener in the head, as shown and described.

DESCRIPTION

FIG. 1 is a perspective view of a key with bottle opener in the head showing my new design;

FIG. 2 is a front elevational view thereof;

FIG. 3 is a rear elevational view thereof;

FIG. 4 is a bottom plan view thereof;

FIG. 5 is a top plan view thereof;

FIG. 6 is a side elevational view thereof; and,

FIG. 7 is a side elevational view thereof, opposite to FIG. 6. The broken lines showing of a key ring and keys are for illustrative purpose only and form no part of the claimed design.
